UNITED STATES PATENT OFFICE

FRANCIS J. CATTERLIN, OF LOS ANGELES, CALIFORNIA

DESIGN FOR A WALKING TOY

Application filed July 21, 1930. Serial No. 36,422. Term of patent 8½ years.

To all whom it may concern:

Be it known that I, FRANCIS J. CATTERLIN, a citizen of the United States, and a resident of Los Angeles, Los Angeles County, California, have invented a new, original, and ornamental Design for a Walking Toy, of which the following is a specification, reference being had to the accompanying drawings, forming a part hereof.

In the drawings Figure 1 is a front ele-

vation of a walking toy showing my new design; and Figure 2 is an edge view including a fragmentary showing of a handle.

The drawing is lined to indicate the colors of red, black and yellow.

I claim:

The ornamental design for a walking toy, substantially as shown and described.

FRANCIS J. CATTERLIN.
